UNITED STATES PATENT OFFICE

MILTON J. WOLFERMAN, OF NEW YORK, N. Y., ASSIGNOR TO CONTINENTAL SILVER COMPANY, OF BROOKLYN, NEW YORK, A CORPORATION OF NEW YORK

SUGAR DISPENSING CONTAINER

Application filed March 7, 1931. Serial No. 520,803.

My present invention relates particularly to dispensing containers of the specific type known as sugar spills which are used in restaurants in place of sugar bowls for the sanitary service of granulated sugar for individual use.

It is an object of the invention to provide a dispensing container of the above type of simple and inexpensive construction, attractive in appearance, easy to handle and readily maintained clean and readily refilled.

Another object is to provide a device of the above type devoid of rubber or other fabric buffer parts yet not apt to be injured or broken even in rough use, and not apt to scratch or abrade the table.

Another object is to provide a dispensing container of the above type, which may be wholly devoid of measuring mechanism or other movable parts, and which yet serves automatically to break up sugar that has become lumpy through moisture.

Another object is to provide a dispensing container of the above type which while affording a relatively large opening not apt to become clogged, yet in use effects inherent retardation so that the rate of feed will normally be sufficiently slow to avoid waste or over-sugaring.

Other objects will be in part hereinafter pointed out.

In the accompanying drawings in which is shown one of various possible embodiments of the several features of the invention,

Fig. 1 is a view in longitudinal cross-section of a preferred form of sugar spill,

Fig. 2 is a transverse sectional view taken on line 2—2 of Fig. 1, and

Fig. 3 is a fragmentary view on a greatly enlarged scale showing the construction of spill cover.

Referring now to the drawings, there is shown a container or jar 10 of thick glass which may be clear or of any desired color and presents preferably a smooth, slightly flaring inner wall 11 and a polygonal or prismatic outer wall 12 illustratively in the form of a regular octadecagon.

The bottom of the container is of considerable thickness as at 13 and the lower face

thereof is preferably concave as at 14 affording a support rim.

Integral with the bottom of the jar is a protruding unitary bead 15 preferably semi-circular in cross-section, at which the vertices of the prism construction terminate. The bead is encircled by a pewter, white metal or other soft metal ring 16 preferably spun as shown over the upper edge of the bead and into the outer periphery of the concave bottom as at 17.

By the construction last described, the soft metal ring is securely affixed and yet affords sufficient freedom of movement relative to the glass to serve as a protector which guards the glass from impact tending to break the bottom off or to chip it at the edge most freely exposed. The soft metal ring maintains all glass parts out of contact with the table and thus protects a glass, marble composition or wooden table top from becoming scratched or abraded by the hard glass.

At the rim, the container is preferably provided with a single turn of thread 18 for the removable spill cover 19, said thread having therebelow a unitary peripheral stop bead 20.

The spill cover is preferably stamped or spun from a unitary sheet of metal and affords a cylindrical flange 21 into which is frictionally held a threaded sleeve 22, for coaction with the threads of the jar, said sleeve having a unitary, out-turned, reinforcing, protective bead 23 encircling the rim of flange 21 and which when the cover is applied to the container, comes into contact with the glass bead 20. The cover has a generally upstanding conical end face 24 with an opening 25 preferably at its apex, of diameter preferably in the order of $\frac{3}{8}$ " through which the sugar may be spilled.

The metal immediately about the opening is preferably turned inward in an ornamental crater-like formation 26 which affords an annular groove 27 immediately about the opening, the inner rim of which groove constitutes the free edge cut away when the central opening 25 is stamped out.

Preferably the rim of the opening 25 is left unfinished and in fact preferably roughened as shown at 28 for a purpose which will

appear more apparent in setting forth the operation below. It is noted here however that the free edge though rough and sharp is in such inaccessible and protected position that the user cannot touch the same and injury to the fingers or hands is avoided.

The heavy bottom of the device enhances its stability and its strength. The protective ring 16 as previously set forth guards 10 against injury to the sugar spill in handling the same and against abrasion of the table. The prism effect of the glass also affords a design of ornamental appearance and provides a convenient non-slipping handle. 15 Even when the container is completely filled, the sugar must drop at least through the height of the conical cover when the spill is inverted for use. In such action, any large lumps of sugar are broken up by falling past 20 the rough or sharp cutting edge 28 of the spill opening. In general the sugar slides along the surface and is retarded in moving over the groove 27 and the sharp edge so that uncontrolled feed is obviated. It is easy 25 accordingly to fill a teaspoon by spill from the device, without loss.

The device consists only of the two separate parts, the glass container 10 and the removable metal cover 19. There are no gas- 30 ket or rubber parts subject to decay and no measuring mechanism or other movable parts subject to jamming or apt to become other- wise deranged.

It will thus be seen that there is herein 35 described a device in which the several features of this invention are embodied, and which device in its action attains the various objects of the invention and is well suited to meet the requirements of practical use.

40 As many changes could be made in the above construction and many apparently widely different embodiments of this invention could be made without departing from the scope thereof, it is intended that all matter contained in the above description or 45 shown in the accompanying drawings shall be interpreted as illustrative and not in a limiting sense.

Having thus described my invention, what 50 I claim as new and desire to secure by Letters Patent is:—

1. A sugar spill comprising a transparent jar having a spill cover, a unitary outstanding bead at the bottom of the jar and a soft metal protective ring about the bead.
2. A sugar spill comprising a glass jar having a thick bottom provided with a unitary outstanding bead and a metal ring spun around said bead for protective purposes, said jar having a spill cover.
3. A sugar spill comprising a unitary heavy glass generally cylindrical container having a thick bottom with a concave under- 65 surface and a unitary outstanding bead and

a soft metal ring spun over the rim of said bottom and encircling said bead.

4. A sugar spill comprising a container having a generally conical cover with an in- turned crater-like spill opening presenting 70 a flow retarding trough about said opening.

5. A sugar spill comprising a container having a stamped metal cover movably af- fixed upon the mouth thereof, said cover hav- 75 ing a fastening rim associated with said con- tainer and an upstanding conical confor- mation with an opening at its apex, the metal of said cover being inturned in crater forma- 80 tion about said spill opening to dispose the free edge of said opening in inaccessible po- sition on said cover, the edge of the opening being left unfinished.

6. A sugar spill comprising a cylindrical glass container having a thick side wall and 85 a thick bottom, a unitary bead about the bot- tom, a soft metal ring spun about said bead, a threaded construction at the mouth, a uni- tary bead immediately below said threaded construction and a removable sheet metal cover adapted to be threaded over said mouth 90 and having a central spill opening.

Signed at New York, in the county of New York and State of New York, this 5th day of March A. D. 1931.

MILTON J. WOLFERMAN.
